卷之三

UNITED STATES PATENT OFFICE.

EDGAR P. COLEMAN, OF BUFFALO, NEW YORK.

METHOD OF OPERATING GAS-PRODUCERS.

No. 888,785.

Specification of Letters Patent.

Patented May 26, 1908.

Application filed January 25, 1908. Serial No. 412,591.

To all whom it may concern:

Be it known that I, EDGAR P. COLEMAN, a citizen of the United States, and a resident of Buffalo, Erie county, New York, have invented certain new and useful Improvements in Methods of Operating Gas-Producers, of which the following is a full, clear, and exact description, such as will enable others skilled in the art to carry out and 10 use the same.

My invention relates to an improved method of operating gas producers.

The object of my invention is to enable the utilization of exhaust steam in gas producers and particularly to convert a variable supply of steam into a substantially invariable supply at the gas producer, as required to produce the best results.

My invention will be readily understood upon reference to the accompanying drawings forming a part of this specification and in which I have illustrated apparatus for carrying my invention into effect; to-wit, for maintaining a substantially constant 25 pressure and supply of steam at the twyer of a gas producer.

Figure 1 illustrates a complete system of this kind; and Fig. 2 is a detail view illustrating a modification of the form and arrangement of the steam blower or compressor.

In the drawings, 2, represents a gas producer and 3 the twyer thereof. This particular producer is of the kind known as a 35 pressure gas producer, the same being supplied with steam and air, both under pressure.

Those who are skilled in the art will readily understand that my invention is 40 just as readily applicable to suction gas producers; the latter are distinguished from the former by a suction fan or pump which withdraws the gas from the top of the producer. A vacuum is created in a suction 45 gas producer and the necessary quantity of air is drawn into the producer through the twyer; as distinguished from the forcible introduction of the air, in the case of a pressure gas producer.

50 In Fig. 1, 4, represents the mixing box at the end of the twyer. 5 and 6 are the air and steam pipes that are connected to the mixing box, 4, the first containing a back check valve, 7, to prevent a back flow of gas 55 from the producer. The air is supplied by a blast fan, 8, which is operated at a sub-

stantially constant speed by a suitable motor, not shown. 9 represents a receiver or air trunk into which the fan discharges and wherein a constant pressure of air is maintained. 10 represents a steam receiver or trunk corresponding to the air receiver, 9, and wherein, by the means hereinafter described, a constant pressure of steam is maintained. The pressures of air and steam in the receivers, 9 and 10, are so proportioned as to yield the desired mixture of the two in the twyer of the gas producer and said pressures being maintained, (i. e. controlled by valves) it is obvious that the mixture will continue at a constant pressure throughout the period of the operation of the gas producer.

It will be understood that the gas producer herein shown represents one of a 75 series or row of producers and that the receivers, 9 and 10 serve the entire group. When a steady and continuous supply of either live or exhaust steam is economically obtainable, the steam supply pipe may be 80 connected directly to the receiver, 10. But this is seldom the case, particularly where exhaust steam is to be used. The supply of exhaust steam at any plant necessarily varies in accordance with the changing loads 85 upon the engines used in the plant. So far as I am informed all attempts to use exhaust steam under such circumstances have failed because of the fluctuation of the pressure and volume of the steam delivered to 90 the gas producer. I take the steam having variable pressure due to fluctuations in the quantities in which it is supplied from the engines and reduce said variations of pressure to a smaller range by means of a steam 95 regenerative accumulator and then variably compress the steam at a point near the producers, thereby maintaining a constant pressure at the producers. As well shown in the drawings I employ two separate agencies; 100 first, a steam - regenerative accumulator adapted to take up an excess of steam when the supply is greater than the demand at the producers and to give off steam when the opposite condition prevails; and, second, a 105 constant pressure steam compressor arranged between the regenerative accumulator and the gas producer and adapted to maintain the desired terminal pressure at the producer.

110 Referring again to the drawings, 11, represents the exhaust steam pipe or main and

12 a relief valve which is open to atmosphere and determines the maximum pressure in the main, 11.

13 is an oil separator; 14 is a live steam connector containing a reducing valve, 15, adapted to admit live steam to the exhaust main at a pressure somewhat lower than that at which the relief-valve operates.

A represents the steam-regenerative accumulator which is joined to the exhaust main by a pipe, 16. This part of the apparatus comprises a drum or shell, 17, adapted to contain a body of water, 18, and means for rapidly circulating the water; said means comprising the pump, 19, a connection, 20, near the bottom of the drum and a sprayer, 21, to which the pump delivers the water drawn through the connection, 20. The water stands at a level below the sprayer and the pump, 19, is continuously operated to constantly throw or spray the water into the space, 17'. This space is occupied by steam from the exhaust main and it is obvious that the intimate admixture of the steam and the water through the agency of the spray, causes the water to take on approximately the same temperature as the steam. The maintenance of this heat relation is insured by the rapid circulation of the water. Mere exposure of the surface of the body of water to the steam would not accomplish the result. When the supply of steam increases from a less to a greater pressure in the exhaust main, the temperature of the steam likewise increases and the steam entering the accumulator gives up its excess heat to the water. A portion of excess energy of the steam is thus stored in the water of the accumulator to be available during the time of a future deficiency. On the other hand when the steam pressure decreases, the reduction of the pressure in the steam space of the accumulator causes evaporation of the water which at the instant possesses a higher temperature, thus a large body of steam proportional to the degree and duration of the temperature drop, is restored to the exhaust main and tends to maintain a desired constant pressure therein. Should the flow of exhaust steam be interrupted for such a length of time as to exhaust the capacity of the regenerator, the reducing valve, 15, automatically admits live steam to make up the deficiency.

Theoretically the regenerative accumulator could be made so large that the temperature and pressure variations would be negligible, but from a practical standpoint this would not be economical by reason of the great cost and losses of an accumulator of such size. I therefore secure the economic advantages obtainable from a fluctuating supply of exhaust steam by using a relatively small regenerative accumulator and employ a separate device for preventing fluctuations of pressure at the twyer of the gas producer. The device referred to is the displacement pump or compressor B. This is interposed in the steam pipe, 11, between the accumulator and the producer. It draws steam from the pipe section, 11', and discharges it into the section, 11'', which latter is connected with the receiver, 10. For driving the pump I employ a motor, 22, adapted to operate at varying speeds and governed by a regulator, 23. The normal speed of the pump is sufficient to maintain the desired pressure in the receiver, 10, at times when normal conditions prevail in the steam main. If the pressure, *i. e.*, supply, diminishes, the speed of the pump is increased to maintain the pressure at the receiver, 10, and when there is an increase of pressure in the exhaust main, the speed of the pump is decreased to prevent an excess of pressure at the receiver. This is accomplished by the regulator, 23, which, as shown, is connected with the pipe, 11'', to be influenced by the slightest change of pressure therein. $b'-b'$ are valves for shutting off the pump connections and b'' is a by-pass containing a valve, b''' , which may be opened when the pump is shut down. This apparatus effectively preserves the supply of steam at the producer so long as it is supplied, either directly from the exhaust main, the accumulator or the live steam connection.

A detail which is necessary for the operation of the regenerative accumulator comprises the fresh water deficiency connection, a' , having a float actuated regulating valve, a'' , whereby the proper quantity of water is maintained in the drum, 17, also a float controlled overflow valve, a^3 .

In lieu of the displacement pump illustrated in Fig. 1, I may use a centrifugal pump, B'; with means for operating the same at variable speed. In this case I prefer to connect the live steam pipe, 14', to the terminal section of the steam pipe and also connect the valve thereof with the regulator, 23', in such manner that live steam is admitted only when the pump has attained its maximum speed.

As various modifications of my invention will readily suggest themselves to one skilled in the art, I do not confine the invention to the specific steps herein described.

Having thus described my invention, I claim as new and desire to secure by Letters Patent:

1. The herein described method of operating gas producers which consists in subjecting exhaust steam to a reduction of pressure, then compressing the steam and simultaneously supplying the compressed steam and air to the producer, substantially as described.
2. The herein described method of operating gas producers with exhaust steam,

- which consists in reducing the pressure of exhaust steam, compressing said steam, maintaining the pressure of the compressed steam constant, supplying the compressed steam and air to the producer and alternately extracting and supplying steam from and to the initial supply of steam to reduce the pressure variations at the compressor, substantially as described.
3. The herein described method of operating gas producers which consists in compressing low pressure exhaust steam derived from a suitable source, maintaining the pressure of the compressed steam constant, supplying live steam to the compressor when the supply of exhaust steam falls below a maximum and simultaneously supplying the compressed steam and air to the gas producer, substantially as described.
4. The herein described method of maintaining the terminal pressure of a supply of steam which consists in subjecting a portion of the steam to the action of a confined body of violently agitated water partly in the form of spray at a point between the source of supply and the place of use, substantially as described.
5. The herein described method of maintaining the terminal pressure of a supply of steam which consists in subjecting the steam to the action of a confined body of violently agitated water partly in the form of spray at a point between the source of supply and the place of use and compressing the steam in its conduit at a point between said place of use and the point of exposure to the water, substantially as described. 30
6. The herein described method of operating gas producers with exhaust steam which consists in taking steam having a variable pressure due to fluctuations in the quantity supplied, reducing said variations of pressure to a smaller range by means of a steam regenerative accumulator and compressing the steam to a constant pressure at 40 the producer, substantially as described. 45

In testimony whereof, I have hereunto set my hand, this 30th day of November, 1907, in the presence of two subscribing witnesses.

EDGAR P. COLEMAN.
